Primary Examiner — Mark A Goodwin*(74) Attorney, Agent, or Firm* — Rebecca L. Henkel; Rickard K. DeMille(57) **CLAIM**

The ornamental design for a seed conduit, substantially as shown and described.

DESCRIPTION

FIG. 1 is a perspective view of a seed conduit;
 FIG. 2 is a front view of the seed conduit;
 FIG. 3 is a back view of the seed conduit;
 FIG. 4 is a right side view of the seed conduit;
 FIG. 5 is a left side view of the seed conduit;
 FIG. 6 is a top view of the seed conduit; and,
 FIG. 7 is a bottom view of the seed conduit;
 Phantom lines, where utilized, are for illustrative purposes only and form no part of the claimed design.

1 Claim, 4 Drawing Sheets(56)
